UNITED STATES PATENT OFFICE.

HENRY MCVITTIE, OF BEND, OREGON.

TRANSOM-OPERATOR.

1,280,510.

Specification of Letters Patent. Patented Oct. 1, 1918.

Application filed July 12, 1917. Serial No. 180,144.

To all whom it may concern:

Be it known that I, HENRY MCVITTIE, a citizen of the United States, residing at Bend, in the county of Deschutes and State 5 of Oregon, have invented certain new and useful Improvements in Transom-Operators; and I do hereby declare the following to be a full, clear, and exact description of the invention, such as will enable others 10 skilled in the art to which it appertains to make and use the same.

This invention relates to a device for opening and closing transoms and the primary object of the invention is to provide a 15 transom operator, which is operated by the inward pressure upon a button, which may be carried by the door frame in a position for convenient access by anyone desiring to operate the transom.

20 A further object of this invention is to provide a locking mechanism for locking the transom operating mechanism against accidental movement, so as to hold the transom in various adjusted positions and to provide 25 a second push button which is carried by the first or transom operating push button for releasing the locking means, and to arrange the locking means and the push button for operating the same so that the inward pressure 30 upon the locked operating push button will first release the lock and further inward pressure upon the buttons will operate a series of pinions and rack bars which will in turn operate a crank arm for pivotally moving the transom.

With the foregoing and other objects in view this invention consists in such novel features of construction, combination and arrangement of parts as will be hereinafter 40 more fully described, illustrated in the accompanying drawings and claimed.

In describing the invention in detail reference will be had to the accompanying drawings wherein like characters designate 45 like and corresponding parts throughout the several views, and in which—
Figure 1, is an elevation of a door structure showing the improved transom operator applied thereto;
Fig. 2, is a section on the line 2—2 of Fig. 1;
Fig. 3, is a vertical section through the

transom operator taken on the plane of the line 3—3 of Fig. 2,

Fig. 4, is a vertical section through a part 55 of the transom operating mechanism taken on the plane of the line 4—4 of Fig. 2,

Fig. 5, is a vertical section through a part 60 of the transom operating mechanism taken on the plane of the line 5—5 of Fig. 2, and

Fig. 6, is a detail perspective of a part of the push button structure for operating the transom.

Referring more particularly to the drawings, 1 designates an ordinary door frame, 65 the upper section of which has a transom 2 pivotally positioned therein and supported by the usual type of trunnions or pivot pins 3. The transom 2 has a member 4 attached thereto above its pivot, which member has ears 5 carried thereby to which ears a bar 6 is pivotally connected as shown at 7. The bar 6 is connected to a rod 8, which extends transversely from the upper end of a bar or lever 9. The bar 9 has its lower end formed 70 upon one end of a shaft 10 and in fact the pin 8 and the arm or bar 9 form a crank upon the shaft 10 which is connected to the bar 6 for pivotally moving the transom 2 upon the rocking or rotating of the shaft 10. 75 The shaft 10 is supported by suitable bearings 11, which are in turn attached to the casing of the door structure.

The shaft 10 has a pinion 12 mounted thereon, which meshes with rack teeth 13 85 formed upon the upper end of a bar 14. The bar 14 extends downwardly along the casing of the door structure and has rack teeth 15 formed upon its lower end. The rack teeth 15 extend into a casing 16, and they mesh 90 with a pinion 17 which is mounted upon a shaft 18. The shaft 18 is rotatably supported by suitable supporting plates 19 and 20 which are positioned within the housing 16 and it has a second pinion 21 mounted 95 thereon. The pinion 21 meshes with the rack teeth 22 which are formed upon the upper surface of the plunger 23. The plunger 23 has an enlarged head or button 24 formed upon its outer end which is slidably carried by a suitable substantially cylindrically-shaped guide 25. The button or head 24 is hollow, and has a plate 26 removably mounted 100 over its outer end as clearly shown in

Figs. 2 and 4 of the drawings. A bar or buffer 27 is formed upon the inner end of the plunger 23 and it has a pair of contractile springs 28 connected thereto which are seated in recesses 29 formed in the bearing members 19 and 20 and they have their innermost ends connected to the bearing members for moving the buffer 27 inwardly toward the casing 16 and for forcing the button or head 24 outwardly.

When the button 24 is moved inwardly within the casing 16, the meshing engagement between the pinion 17 and the rack teeth 15 will move the bar 14 vertically, which will, through the meshing engagement of the rack teeth 13 with the pinion 12 rotate the shaft 10 and consequently rotate the crank mechanism composed of the arm 9 and rod 8 about the axis of the shaft 10 for swinging the transom 2 upon its pivot 3 into an open position, and when the plunger 23 and head 24 are forced outwardly by the action of the springs 28, the bar 14 will be moved in an opposite direction which will rotate the shaft 10 in an opposite direction and swing the transom upon its pivot 3 to a closed position.

A lock structure is provided for holding the transom in adjusted pivotal position, and this lock structure includes a locking pin 30 which is slidably carried by a suitable support 31 which is formed upon the plunger 23. The support 31 is substantially U-shaped and the pin 30 has a collar 32 formed thereupon which engages the inner surface of the outer leg or side 33 of the U-shaped supporting bracket 31 for limiting the outward movement of the locking pin 30. A spring 34 is coiled about the locking pin 30 and it tends to force this pin outwardly into one of the spaced openings 35 formed in the keeper 36 so that when the pin 30 is seated in any one of the spaced openings 35, the plunger 23 will be held against movement which will in turn hold the transom 2 against pivotal movement.

The locking pin 30 has a shank 37 formed thereupon which is slidably seated in the plunger 23. The shank 37 has an opening 38 extending transversely therethrough, one side of which is inclined throughout a portion of its distance as shown at 39 in Fig. 2 of the drawings. The plunger 23 is provided with a bore 40 in which is slidably mounted a pin 41. The pin 41 has a head 42 formed upon its outer end which projects through the closing plate 26 of the cap 24. A spring 43 is coiled about the pin 41, and has one end connected to the pin and the other end to the plate 26 so that the action of the spring will hold the pin 41 outwardly except when it is forced inwardly by manual pressure. The inner

end of the pin 41 is inclined or cut angularly 65 as shown at 44 so that when the pin 41 is forced inwardly, the angled end 44 will ride over the angled side 39 of the opening 38 and the movement of the pin into the opening 38 will force the locking pin 30 70 longitudinally within the transverse slot which is formed in the plunger 23 and this movement will force the end of the locking pin out of the opening 35, so as to permit the plunger 23 to be moved either inwardly 75 for opening the transom or outwardly for closing the transom.

In the operation of the improved transom operator, the pin 41 is first forced inwardly which releases the catch structure and moves 80 the head 42 into engagement with the outer surface of the plate 26 so that further inward movement will move the plunger 23 inwardly and rotate the shaft 18 through the meshing engagement between the teeth 85 22 formed upon the plunger and the pinion 21 which is carried by the shaft 18. The rotation of the shaft 18 will be administered to the shaft 10 through the medium of the pinions 17 and 12 and the bar 14 as previously described.

From the foregoing description taken in connection with the accompanying drawings the advantages of construction and of the method of operation of the improved 95 transom operator will be readily apparent to those skilled in the art to which this invention appertains and, while in the foregoing description the principle of the operation of this invention has been described together 100 with various features of construction, it is to be understood that certain minor features of construction, combination and arrangement of parts may be altered to suit practical conditions provided such alterations are comprehended within the scope 105 of what is claimed.

What is claimed is:—

1. In a transom operating mechanism, the combination with a pivoted transom, of a 110 shaft, means connecting said shaft to said transom for swinging the transom upon a rotary movement of the shaft, a plunger, means operatively connecting said plunger to said shaft for rotating the shaft upon 115 longitudinal movement of the plunger, a locking pin slidably mounted in said plunger, a keeper for receiving said locking pin, and means for holding the locking pin in engagement with the keeper to prevent accidental movement of the plunger.

2. In a transom operating mechanism, the combination with a pivoted transom, of a 120 shaft, means connecting said shaft to said transom for swinging the transom upon rotary movement of the shaft, a plunger, means operatively connecting said plunger to said shaft, for rotating the shaft upon 125

longitudinal movement of the plunger, a locking pin slidably mounted in said plunger, a keeper for receiving said locking pin, said locking pin being provided with an opening adjacent one end, a movable pin carried by the plunger, and adapted to engage the locking pin through the opening in same for moving the locking pin out of

engagement with the keeper for opening or closing the transom. 10

In testimony whereof I affix my signature in presence of two witnesses.

HENRY McVITTIE.
